(57) **CLAIM**

The ornamental design for a corner support platform, as shown and described.

DESCRIPTION

FIG. 1 shows a front perspective view of a corner support platform;

FIG. 2 shows a front elevation view of the corner support platform of FIG. 1;

FIG. 3 shows a rear elevation view of the corner support platform of FIG. 1;

FIG. 4 shows a right elevation view of the corner support platform of FIG. 1;

FIG. 5 shows a left elevation view of the corner support platform of FIG. 1;

FIG. 6 shows a top view of the corner support platform of FIG. 1; and,

FIG. 7 shows a bottom view of the corner support platform of FIG. 1.

The broken lines in FIGS. 1-7 illustrate the environment of the corner support platform and form no part of the claimed invention.

1 Claim, 6 Drawing Sheets
